CLAIM

The ornamental design for a wall mounted bathroom accessory, as shown and described.

DESCRIPTION

FIG. 1 is a top plan view of a wall mounted bathroom accessory showing my new design as embodied in a towel rack, the bottom being a mirror image of that shown;

FIG. 2 is a front elevational view thereof;

FIG. 3 is a rear elevational view thereof;

FIG. 4 is a right side elevational view thereof, the left side being a mirror image of that shown;

FIG. 5 is a top plan view of a wall mounted bathroom accessory showing my new design as embodied in a shelf, the bottom being plain and unornamented;

FIG. 6 is a front elevational view thereof;

FIG. 7 is a rear elevational view thereof;

FIG. 8 is a right side elevational view thereof, the left side being a mirror image of that shown;

FIG. 9 is a top plan view of a wall mounted bathroom accessory showing my new design as embodied in a towel rack, the bottom being a mirror image of that shown;

FIG. 10 is a front elevational view thereof;

FIG. 11 is a rear elevational view thereof;

FIG. 12 is a right side elevational view thereof, the left side being a mirror image of that shown; and

FIG. 13 is a top, front, and left side perspective view thereof.
